UNITED STATES PATENT OFFICE.

WALTER B. POHLE, OF LYNN, MASSACHUSETTS, ASSIGNOR OF ONE-THIRD TO PARKER B. HASKELL, OF LYNN, MASSACHUSETTS, AND ONE-THIRD TO SUSAN V. RUSSELL, OF CHELSEA, MASSACHUSETTS.

CRANK CASING.

Application filed December 26, 1925, Serial No. 77,843. Renewed December 7, 1926.

This invention relates to crank casings and particularly to crank casings which have formed integral therewith a plurality of transversely disposed splash troughs, the object of the present invention being to provide means adapted to be attached to the bottom of said troughs in which sediment may be collected and withdrawn at will and a new supply of oil admitted to said troughs. 10 Another object of the invention is the provision of a sediment collecting depression formed in the bottom of the casing and provided with a normally closed opening in one wall through which the sediment may be removed from said depression. 15

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and 25 organization of these instrumentalities as herein shown and described except as required by the scope of the appended claims.

Of the drawings:

Figure 1 represents a longitudinal vertical 30 section of a crank casing embodying the principles of the present invention.

Figure 2 represents a transverse section of same on line 2, 2 on Fig. 1, and

Figure 3 represents an enlarged transverse 35 section of one of the troughs showing a sediment receptacle removably secured to the bottom thereof.

Similar characters indicate like parts throughout the several figures of the drawings. 40

In the drawings, 10 is a crank casing the bottom 11 of which inclines downwardly from the opposite ends thereof to a sediment collecting depression 12 formed integral 45 therewith.

Transversely disposed in the crank casing 10 and formed integral therewith are a plurality of splash troughs 13 through each of which the end of a crank 14 passes in its 50 rotation about the axis of the shaft 15 to

which all of the cranks 14 for the various troughs are secured.

Each trough 13 has an opening 16 in the lowest part of its bottom wall 17 communicating with a sediment collecting pocket or receptacle 18 having a flange 19 extending outwardly from its walls, this flange 19 being adapted to be either permanently secured to the under face of the bottom wall 17 of each trough 13 by any well known means as indicated in Figs. 1 and 2 or removably secured thereto as indicated in Fig. 3.

In the construction shown in Fig. 3 a gasket 20 is interposed between the flange 19 and the bottom wall 17 and the flange 19 is secured to said wall 17 by means of screws or bolts 21.

In one wall of the depression 12 is an opening normally closed by a threaded plug 22 which may be removed to give access to the interior of said depression 12 so that the sediment may be removed therefrom, the oil in the casing being discharged at the same time preparatory to the admission of a fresh supply of oil to the casing 10. 75

Each sediment receptacle 18 also has an opening extending therefrom through one wall of the casing which is normally closed by a threaded plug 23 adapted to be removed to provide means for removing the sediment 80 from the receptacle 18 and the oil from the trough 13 to which it is attached.

This cleaning operation may be performed at one trough at a time without disturbing the other troughs. 85

Each trough is provided in one wall with an opening normally closed by a threaded plug 24 which may be removed to admit into said trough a fresh supply of oil.

Many crank casings now in use have the splash troughs thereof formed integral therewith and are provided with no means for removing the sediment collecting therein, except by removing the entire casing and cleaning out the various troughs which occupies considerable time, entails much labor, and places the motor out of commission until the casing is replaced and a fresh supply of oil is installed. 95

These crank casings thus constructed may 100

be used in carrying out the present invention by cutting the openings 16 in the bottom of the various troughs 13 and then welding or otherwise securing a sediment receptacle 18 5 to the under wall 17 of each trough.

The casing 10 itself may have its bottom wall reshaped to form the depression 12 therein.

The threaded openings for the plugs 22, 10 23, 24, may then be drilled, threaded, and these plugs inserted.

When this has been accomplished the casing is so constructed that the sediment in the oil in the various troughs is permitted to 15 pass through the openings 16 in the troughs out of the path of the crank 14 so that the oil in the troughs will be perfectly clear in the trough 13 and no grit or sediment can be splashed upon the various bearings to 20 interfere with the proper working thereof.

Each trough may then be cleaned independently of the others and if one of said troughs is being cleaned and the use of the motor is unexpectedly required, the plug 23 25 may be quickly replaced, the trough 13 being cleansed can be given a new supply of oil and the plug 24 replaced and the apparatus will be ready for immediate use.

This is of prime importance where the 30 motor is installed upon a fire truck or the like which are liable to be called into action at any time during the day and night.

All cleansing operations on these trucks must be performed expeditiously and application has provided a means whereby this may 35 be accomplished.

The sediment receptacles may be made of 40 large capacity if desired so that they may go without cleaning for long periods as when the sediment collects therein there will be no opportunity for it to mix again with the oil in the troughs 13 and interfere with the proper working of the motor.

When a new supply of oil is required for 45 the casing 10 the old oil may be discharged by removing the plug 22, the oil in passing from the outlet carrying with it all the sediment in the depression 12.

It is believed that the operation and many 50 advantages of the present invention will be

fully understood without further description.

Having thus described my invention, I claim—

1. A crank casing having formed integral therewith a plurality of splash troughs extending transversely thereof and through which the ends of the cranks pass during their rotation, each trough having an opening in the lowest part of its bottom and a sediment receptacle fixedly secured to the under face of said bottom of each trough and always in communication with said opening.

2. A crank casing provided with a plurality of splash troughs extending transversely thereof and through which the ends of the cranks pass during their rotation, each trough having an opening in the lowest part of its bottom and a sediment receptacle secured to the under face of said bottom and communicating with said opening, one wall of the casing being provided with an outlet from said receptacle normally closed by a removable plug.

3. A crank casing provided with a plurality of splash troughs extending transversely thereof and through which the ends of the cranks pass during their rotation, each trough having a sediment pocket in the lowest part of its bottom below the path of the crank, and an opening in one wall of the casing for each trough normally closed by a removable plug and through which a fresh supply of oil may be admitted to said trough.

4. A crank casing provided with a plurality of splash troughs extending transversely thereof and through which the ends of the cranks pass during their rotation each trough having a sediment pocket in the lowest part of its bottom below the path of the crank, and said casing having at the lowest part of its bottom a sediment collecting depression provided with an opening in a wall thereof normally closed by a removable plug and through which the sediment may be removed from said depression.

Signed by me at 746 Old South Bldg., Boston, Mass., this 24th day of November, 1925.

WALTER B. POHLE.
